UNITED STATES PATENT OFFICE.

HIRAM S. LASHER, OF NEW YORK, N. Y., ASSIGNOR TO UNDERWOOD TYPEWRITER COMPANY, OF NEW YORK, N. Y., A CORPORATION OF DELAWARE.

TYPEWRITING MACHINE.

1,409,189.

Specification of Letters Patent. Patented Mar. 14, 1922.

Application filed July 9, 1919. Serial No. 309,711.

To all whom it may concern:

Be it known that I, HIRAM S. LASHER, a citizen of the United States, residing in the borough of the Bronx, in the county of the Bronx, city and State of New York, have invented certain new and useful Improvements in Typewriting Machines, of which the following is a specification.

This invention relates to typewriting machines, and particularly to means for facilitating the writing of entries upon sheets like the ledger-sheet used by stock brokers and others who desire to make, upon a single record-sheet, the records of the entries that are written upon a large number of sheets.

The invention may be carried out in one way by employing a machine of the type illustrated in the Wernery & Smith Patent, No. 1,132,055, in which the revoluble platen is displaceable upwardly for convenience in manipulating the sheets, and in which the carbons may be shifted back from time to time relatively to the web or webs upon which the condensed records are to be made.

In carrying out the invention, the leading ends of one or more webs or plies (which may be either separate or in fan-fold form) are led around the platen and adjusted up in front thereof, and the leading edges are caught by a clip provided upon a carrier which is used to advance the webs as the same are typed. The carbons, or most of them, may be arranged between the plies and connected to the blades of the carbon-carrier, as set forth in said patent. The outside sheet, which may be a ledger sheet, is now introduced to occupy a position upon the platen in front of the webs, so that the ribbon copy will be typed upon the ledger-sheet while the web or webs will bear the carbon type impressions. The carbon sheet, that lies between the ledger sheet and the lower sheet of the web, is advantageously caught by the clip together with the front edges of the web.

In order to introduce the ledger-sheet, the platen is shifted up in the manner set forth in said patent, and the web is introduced horizontally, bottom edge first, back between the front of the platen and a guiding apron which may be the usual knife and therefore stands a little in front of the platen. When the platen has been displaced, as aforesaid, it overlies the apron or guide so that the rear or bottom edge of the

sheet may be very readily inserted between the knife and the platen. The ledger-sheet may be then shoved backwardly to about the position for typing a line thereon and accurately positioned by a back scale. Then the platen may be dropped or restored to its printing position, and, if necessary, the leading edge of the ledger-sheet may be adjusted to a scale which extends vertically or inclined backwardly from the delivery side of the platen. The scales are numbered at intervals to agree with the intervals of the horizontal lines ruled upon the ledger-sheet. If the typing is to be done upon line "1" of the sheet, then the leading edge of the sheet is adjusted to the figure "1" on the scale, and so on; the lines upon the sheet being preferably numbered from top to bottom of the sheet, while the scale is numbered from bottom to top thereof, correspondingly. During this final adjustment of the ledger-sheet to typing position, if there are bottom feed-rolls and casting off means therefor, they may be cast off from the platen, or the adjustment may be effected just before the platen reaches its printing position and while it is still separated a little from the feed-rolls.

The operator then types the line upon the ledger-sheet and carbon copies thereof are produced upon the ply or plies of record-web.

At the completion of a line of writing, the operator rotates the platen by means of the usual line-space handle, at the same time returning the platen or carriage to position to begin a new line. Since it is often the practice to make only a single line entry upon the ledger-sheet, the line-spacing mechanism may be regulated so that the platen is advanced two line-spaces at the return of the carriage. This produces a blank line between the entries upon the condensed record-sheets or webs.

After thus line-spacing the sheets, the operator advances the carrier to which the leading edges of the webs are clipped. This carrier may be mounted upon a track, which extends upwardly and rearwardly from the delivery side of the platen parallel with the scale aforementioned. The track may have notches at intervals equal to the line-spacing movements of the platen to detain the carrier at the proper point in each instance. In some forms of the device the carrier may be

automatically advanced, as by the line-space mechanism.

The item being thus typed and the line-spacing being thus attended to the next step 5 may be to replace the typed ledger-sheet by a second ledger-sheet. In performing this operation, the platen may be first displaced upwardly to bring all the sheets to horizontal condition, as in said patent, and then the 10 second sheet is introduced while the first remains in the machine. The second sheet is thrust backwardly, bottom edge first, advantageously between the first record-sheet and the platen so that the first sheet forms 15 an apron for guiding the second sheet into the machine, this being a great convenience. Thereupon, the operator retains the second sheet in the machine while he withdraws the first sheet which is then ready for restoration 20 to the ledger. The second sheet is then manipulated in the manner already described respecting the first sheet, that is, the platen is swung downwardly and the second sheet is adjusted to the point "1," "2," "3," or 25 whatever it might be upon the scale corresponding with the line upon which the typing is to be done on the record sheet.

The ply or plies of web are preferably provided with transverse perforations at suitable intervals, say of 10, 12, or 14 inches, as 30 may be desired, so that after one of these lengths of web is filled with typed copies of the record or ledger-sheet, it may be readily torn off from the web. Before this is done, 35 however, the carbon-carrier is thrust back to withdraw the carbons from the typed portion of the webs, so that they will not be torn off, and to bring them into position for use with the next section of the web, this operation 40 being explained in said patent. Thus, the operation of making condensed records upon sheets of uniform size may proceed until the web or plies are used up.

Other features and advantages will hereinafter appear.

In the accompanying drawings,

Figure 1 is a fragmentary perspective view of an Underwood fan-fold continuous billing machine of the kind referred to, and 50 showing my invention as applied thereto.

Figure 2 is a perspective view, showing the platen and some adjacent parts, and showing the webs and record sheet as ready for writing.

Figure 3 is a diagrammatic, sectional side view, showing the slack in the web after it has been advanced by the platen and before the clip has been advanced to hold it stretched out.

Figure 4 is a face view of one kind of work-sheet adapted to be used in this machine.

Figure 5 is a sectional side view of the platen and adjacent parts in normal writing 65 position.

Figure 6 is a fragmentary rear view of the slide upon which the clip is mounted.

Figure 7 is a dissected perspective view of the clip, showing the relationship of the parts.

Figure 8 is a sectional view of the clip, as seen looking along the slide on which it is mounted.

Figure 9 is a sectional side view of the principal parts associated with the platen 75 when the platen is thrown up to permit the insertion of a new work-sheet.

Figure 10 is a perspective view of a modification having a device for advancing the clip automatically.

Figure 11 is a section through a clutching device for drawing on the cord which advances the clip.

Figure 12 is a side view, partly in section, of the parts shown in Figure 10.

Figure 13 is a plan view of the connections between the line-space mechanism and the cord for advancing the clip.

Figure 14 is a fragmentary perspective rear view of a support to show the scale 90 thereon.

In the Underwood continuous fan-fold billing machine, as machines of the general type of the Wernery & Smith patent are frequently called, the typewriter carriage 1 95 travels upon rails 2, being drawn along by a spring barrel, not shown, at each actuation of a type-bar 3, said type-bars controlling the usual escapement mechanism, not shown. A web or webs 4 are drawn 100 from the rear over the usual rear rod 5 and pass downwardly over a paper table 6 beneath a platen 7 and up in front of the platen, so that the type-bars 3 may print thereon at the usual printing line.

In said machines, the platen is journaled by its axle 8 in a swing frame 9, so as to carry it upwardly and forwardly away from the usual front and rear feed-rolls 10 and 11 into the Figure 9 position, in which position the webs 4 may be drawn forwardly, substantially straight, with the result that they may slip over the usual carbon sheets 12, which are clipped onto the usual carbon paper carriage 13.

For holding the 115 carbon sheets, the carbon carriage 13 comprises side pieces 14 from which project inwardly clip bars 15 alternately on opposite sides of the carriage, so that a carbon sheet 12 clipped to one of said bars may lie between every fold of a fan-folded web. The side pieces 14 of the carriage 13 are mounted upon a bottom plate 16, which is usually adapted to be removed from the body of the carriage, said body including a mounting 17 120 for rolls 18 by which the carriage runs upon the side rails 19. The side rails 19 are rigidly attached to the typewriter carriage 1 by means of brackets 20, and extend rearwardly to the cross-piece or rod 5, and each 125

130

rail has depending therefrom an ear 21, on which is journaled a roll 22, which travels upon the usual rail 23 which serves to support the rear end of the rails 19. Normally, 5 the platen, as has been stated, lies against the feed rolls 10 and 11, and it is adapted to be locked down in that position by means of hooks 24, which are fast upon a shaft 25 and hook over rolls or ears 26 upon the swing 10 frame 9. In Figure 14 the hook and ear are shown outside of the swing frame, to avoid interference with other parts described below.

When the typist desires to insert a sheet, 15 in the manner illustrated in Figure 9, the typist presses rearwardly a finger-piece 27 forming an extension of one of the hooks 24, thus releasing the swing frame, and then the typist swings the swing frame forwardly, usually by grasping the upper front 20 paper table 28 or some extension thereof. When the swing frame reaches the Figure 9 position, it is supported by means of bumpers, not shown, thus leaving the hands of the 25 typist free to manipulate the work-sheets. The device of the present invention is especially adapted to enable loose work-sheets to be used in connection with continuous webs 4, which may be fan-folded or not, as desired. 30 When the web or webs 4 and carbon sheets 12 are all ready in the machine and have been written on by the types 3, receiving the impressions thereof through the carbon sheets 12, the typist withdraws the old 35 loose work-sheet 29 already in the machine after inserting the new work-sheet.

To conveniently accomplish this, the old work-sheet 29 is allowed to remain in the machine while a new work-sheet 30 is being 40 inserted, and the new work-sheet is inserted between the old work-sheet 29 and the outside carbon sheet 31 of the sheets 12 on the carbon carriage 14. The outside carbon sheet 31, together with the other carbon 45 sheets and the web sheets, is advantageously held by a clip 32 adjustable upon an extension or support 33 of the paper table 28. Thus, the work-sheet 30 when inserted and pushed rearwardly is unable to drag the outside carbon 31 rearwardly with it. Each 50 new and old work-sheet 29 and 30 is usually in the form of a record sheet having a body 34, which may or may not be provided with suitable rulings, said record sheet also having an extension 35 at its bottom to serve 55 for binding purposes. Where sheets of this character are used, the old work-sheet 29, even when its last line has been written upon, will lie in the position shown in 60 Figure 9 at the time it is to be removed, its lower extension 35 lying upon or extending behind a guide 36 which forms the top of the paper table 37. This being the case, the old work-sheet 29 guides the new work-sheet 30 up over the guide 36 and backwardly over it

as far as the purposes of the work in hand may require, said new work-sheet curving, as it may happen to, downwardly beneath the carbon paper carriage 13, or resting on intermediate rods thereof, not shown. There 70 is little tendency for the work-sheet 29 or for the webs 4 to sag between the guide 36 and the clip 32, since both pass between a knife 38 and the platen 7, said knife forming part of the usual swing frame 9. When a new 75 work-sheet has been inserted in this way, it may be aligned by means of a scale 39 upon the back of an extension 40, which may be provided according to my invention. If the head of the new work-sheet 30 is so short 80 that its upper end is concealed by the webs 4 when the first writing line reaches substantially its proper position, it may be inserted to any convenient position by the typist, and then the swing frame 9 may be 85 swung toward its Figure 1 position, but not in contact with its feed-rolls 10 and 11, thus permitting the new work-sheet 30 to be accurately aligned, since it then is adjacent a scale 41 upon the extension 40, and may 90 have its side held against the turned-up edge 42 of the extension 40. When so positioned and held, the sheet is properly aligned, and the carriage and the swing frame 9 may be then swung rearwardly to clamp the work-sheets and webs in position by bringing the platen against the feed rolls 10 and 11. The writing may then proceed in the usual 95 manner.

The entries in the work for which this 100 type of machine is especially adapted very often consist of only a single line apiece. If this is the case, the typist actuates the usual line-space lever 43 at the end of a line, thus carrying rearwardly the line-space pawl 44, 105 to turn a double line-space the usual line-space wheel 45, which, in machines of the continuous fan-fold billing type, is fast to a pinion 46. To connect the pinion 46 with the platen 7, there is usually provided in 110 machines of that kind a broad pinion 47, which meshes with the pinion 46, and also meshes with the pinion 48 fast to the axle 8 of the platen 7. When the line-space lever has been actuated in this way, the web and 115 associated carbon sheets will appear as in Figure 3, bending into a bight or loop 50, the looseness of which will vary with the advance of the platen by the line-space lever, which is adapted to variably turn the platen 120 according to the setting of the usual lever 49.

Before removing from the machine the sheet written on, which is now the sheet 29, the typist slips the clip 32 upwardly along its support 33 a distance of a double line-space, i. e., the amount the platen has been turned, this serving to separate the item just written clearly from the item to follow. To do this conveniently, the clip 32 comprises a sliding body 51 having ears 52 in which is 125 130

mounted a pawl 53, whose nose 54 is adapted to catch in the depressions of a rack 55 cut upon the back of the slide or extension 33, said rack advantageously being in the form 5 of shallow teeth cut out of the plain surface of the extension 33. The typist will almost automatically reach up and slip the clip 32 along a couple of teeth to take up the slack of the bight 50, so that the webs then lie in 10 the Figure 5 position. Then the typist releases the swing frame and swings the platen to the Figure 9 position to insert a new work-sheet, as described above. In inserting the new work-sheet, the typist merely notices 15 the number in the column 56 of the line next to be written on, and in inserting the new work-sheet brings the leading edge of the sheet to the scale line correspondingly numbered upon the extension 40.

20 When writing upon the sheets in the Figure 1 position, they lie not only upon the extension 40 at the left-hand edge of the front paper table 28, but also upon an extension 57 springing from the right-hand 25 edge of the paper table 28, said extension 57 being also provided with a turned-up edge 58 to enable the webs to have their sides gaged thereagainst. The webs also lie upon the extension or support 33, and to steady 30 the supports, there is provided a cross-piece 59 which underlies the extensions 40 and 57, and is fast to them and to the extension 33, in any suitable manner. The extensions 33, 57 and 40 may be detachably held to the 35 mounting of the paper table 28 by thumb screws 59.

It will be observed, especially from Figures 7 and 9, that the clip 32 with its body mounting 51 is of considerable length. To 40 enable it to slide down onto the paper table 28, the extension 33 may be in the form of a T having a body 60 which rests upon the bottom of a hollow 61 in the paper table 28, said hollow being large enough to permit the 45 body 51 of the clip to extend as far down as is necessary to seize the leading end of the webs and carbon sheet when writing upon the first line thereof below the usual heading. To enable the clip 32 to seize the work- 50 sheets firmly, it comprises a cross-piece 62 adapted to lie upon the face of the extension 33, and it also comprises side pieces 63 having rabbets 64 adapted to slide along and catch under the edges of the extension 33. 55 The cross-piece 62 may be hatched upon its surface. To hold the sheets against the hatched surface, a hatched jaw 65 may be provided with ears 66 adapted to lie close to ears 67 projecting upwardly from the side pieces 63, so that a pivot bar 68 will hold 60 the jaw 65 in proper position to be swung to and from the cross-bar or piece 62. The jaw 65 is provided with a rearwardly extending tail 69, which is stiff though resilient, and 65 which bears against a cam 70 fast upon a

shaft 71, which is journaled in the ears 52, with the result that when the shaft 71 is turned by its crank extension 72, the cam 70 will force the jaw 65 against the cross-bar 62 against the tension of a spring 73 which 70 usually holds the jaw open. The shaft 71 may serve as a journal for the pawl 53. To accurately align the web and carbon the jaw 65 may comprise ears 74 adapted to serve 75 as a leading edge gage for them.

To permit the typist to shift the clip 32 easily along the extension 33, the pawl 53 has an extension 74 forming a finger-piece for manipulating the pawl, and for shifting the clip 32 up and down the extension 33. 80 When a suitable length of webs has been filled up with entries, this length may be severed from the body by drawing it against the knife 38, the webs being advantageously perforated at suitable regular intervals, as 85 at 75°, in order to indicate the point at which the severing should take place. This is especially advantageous in certain kinds of work, because the detached sections of web are often used as the sheets of stock-ledgers or 90 other ledgers, and for this purpose are bound up in leaves of uniform size. The length of the extensions 33, 40 and 57 required will depend upon the length of the web-sheet to be detached. Usually the heading of the 95 portion of the web to be detached is left blank because it is printed with a title, etc., and for this reason the extension 33 need not bring the clip 32 down to the knife 38.

When a section of web has been completely filled up, the typist releases the clip 32 by rotating the crank 72 and then usually swings the platen upwardly to the Figure 9 position, thus permitting the carbon carriage to be pushed rearwardly by the usual 105 handle 75 to carry the carbon sheets behind the edge of the knife, the webs being held in the meantime by the typist's finger or thumb. Then the typist swings the platen back to writing position, after having drawn the 110 webs forwardly if need be, and then severs the desired portion. Next the typist clips the new ends of the webs and the carbon sheets, including the outer carbon sheet, in the clip 32, and the writing proceeds as 115 before.

In the form of the invention shown in Figure 10, the typist need not advance the webs by pushing up on the clip 32. To avoid the need for doing this, there is shown 120 a device for automatically advancing the webs between entries. To enable the machine illustrated in Figure 10 to be used for making other than single-line entries, the web advancing is illustrated as being actuated by the line-space mechanism. In effecting this, the extension 33 may or may not be provided with the rack, and the clip 32, which slides thereon, may be drawn by a cord 76 which passes around a pulley 77 at 125 130

the top of the extension, so that the stretch of cord pulling on the clip 32 lies along the center of the extension. From this point the cord 76 may be carried around a pulley 78 journaled in and guarded by an ear or loop 79, and be carried downwardly near the extension 40 to a reel 80 journaled upon the hub 81 of the pinion 47, said reel having a diameter equal to or a very little larger than the pitch diameter of the pinion 47, thereby advancing the clip 32 amounts equal to the line-spacing advance of the work-sheets by the platen. In order to make the reel 80 tend to turn with the pinion 47, there is provided a friction clutch between the two comprising a friction washer 82 lying against the body of the pinion 47, and the reel 80 has its face 83 pressed against the washer by means of a spring 84, which is held in place by a nut 85 screwed onto the hub 81. In order to guide the long stretch of the cord 76 along the extension 40, there may be provided a guide pulley 86 journaled in an ear 87 fast on said extension.

25 It will be observed that in every line-spacing operation the clip 32 will advance with the web advancing around the platen, and that when it is desired to draw the clip 32 down to the bottom to attach it to a new end of the web, the reel 80 will slip to permit this, and upon subsequent line-spacing will proceed to wind up the web.

Variations may be resorted to within the scope of the invention, and portions of the 35 improvements may be used without others.

Having thus described my invention, I claim:

1. In a typewriting machine, the combination with a traveling carriage and a revolute platen, of feed rolls, a frame in which said platen is adapted to be swung up clear of said feed rolls to permit plies of web and carbon sheets to be straightened out beneath the platen, and a clip above the 45 platen to hold the web plies and an outside carbon sheet while a work-sheet is being inserted in front thereof.

2. In a typewriting machine, the combination with a traveling carriage and a revolute platen, of feed rolls, a frame in which said platen is adapted to be swung up clear of said feed rolls to permit plies of web and carbon sheets to be straightened out beneath the platen, a clip above the 55 platen to hold the web plies and an outside carbon sheet while a work-sheet is being inserted in front thereof, and a rack upon which said clip is adapted to be set at line-space intervals.

60 3. In a typewriting machine, the combination with a traveling carriage and a revolute platen, of feed rolls, a frame in which said platen is adapted to be swung up clear of said feed rolls to permit plies of web and carbon sheets to be straightened

out beneath the platen, a knife in said frame forming a support for the web when stretched out horizontally at the raising of the platen, and a clip above the platen to hold the web plies and an outside carbon sheet clipped while a work-sheet is being inserted in front thereof, said knife adapted to support a loose typed work-sheet while a new loose work-sheet is inserted between the typed work-sheet and the clipped webs. 75

4. In a typewriting machine, the combination with a traveling carriage and a revolute platen, of feed rolls, a frame in which said platen is adapted to be swung up clear of said feed rolls to permit plies of web and carbon sheets to be straightened out beneath the platen, a clip above the platen to hold the web plies and an outside carbon sheet while a work-sheet is being inserted in front thereof, a line-space mechanism for the 80 platen, and a connection whereby the clip is advanced at the operation of the line-space mechanism.

5. In a typewriting machine, the combination with a traveling carriage and a revolute platen and feed rolls, of a frame in which said platen is adapted to be swung up clear of said feed rolls to permit plies of web and carbon sheets to be straightened out beneath the platen, a paper table above the platen, 90 including a support, a clip slideable along said support to support the web and carbon sheets, a front scale to indicate the work-sheet line at the printing point of the platen, and a carbon paper carriage adapted to be pushed rearwardly when the platen is swung up to withdraw the carbon sheets substantially to the printing line of the 100 platen.

6. In a typewriting machine, the combination with a traveling carriage and a revolute platen and feed rolls, of a frame in which said platen is adapted to be swung up clear of said feed rolls to permit plies of web and carbon sheets to be straightened out beneath the platen, a paper table above the platen, including a support, a clip slideable along said support to support the web and carbon sheets, a front scale to indicate the work-sheet line at the printing point of the platen, a carbon paper carriage adapted to be pushed rearwardly when the platen is swung up to withdraw the carbon sheets substantially to the printing line of the 110 platen, and a scale upon the back of said 115 support numbered to indicate by the leading edge of the work-sheet the line upon said work-sheet which comes to the printing point when the platen is swung back against the feed rolls.

7. In a typewriting machine, the combination with a traveling carriage and a revolute platen, of feed rolls, a frame in which said platen is adapted to be swung up clear of said feed rolls to permit plies of web and 120 carbon sheets to be straightened

carbon sheets to be straightened out beneath the platen, a clip above the platen to hold the web plies and an outside carbon sheet, while a work-sheet is being inserted in front thereof, and a paper table behind the platen extending far enough forward near the top of the platen to catch the bottom binding extension of the work-sheet whose bottom printing line has just been written upon, 10 to enable said bottom extension to guide the new work-sheet rearwardly over the top of the paper table.

8. In a typewriting machine, the combination with a traveling carriage and a revoluble platen, of feed rolls, a frame in which said platen is adapted to be swung up clear of the feed rolls to permit plies of web and carbon sheets to be straightened out beneath the platen, a paper table above the 15 platen and comprising extensions, a turned-up edge on one extension forming a side gage for the web, a turned-up edge on the other extension forming a side gage for a separate work-sheet, and a clip for holding 20 the plies of web and carbon sheets against the table.

9. In a typewriting machine, the combination with a traveling carriage and a revoluble platen, of feed rolls, a frame in which 30 said platen is adapted to be swung up clear of said feed rolls to permit plies of web and carbon sheets to be straightened out beneath the platen, a support above the platen, a clip slidable upon said support and lying 35 close against it to hold the web plies and carbon sheets, a line-space mechanism for said platen, a shaft about which said frame swings, a pinion on said shaft forming part of the line-space mechanism, and a device 40 connected to said pinion to advance said clip.

10. In a typewriting machine, the combination with a traveling carriage and a revoluble platen, of feed rolls, a frame in which 45 said platen is adapted to be swung up clear of said feed rolls to permit plies of web and carbon sheets to be straightened out beneath the platen, a support above the platen, a clip slidable upon said support and comprising 50 jaws adapted to grip the plies of web and carbon sheets, a handle for making said clip effective or ineffective and lying below the plane of the clip support, and means for detaining said clip on the support at 55 line-space intervals.

11. In a typewriting machine, the combination with a traveling carriage and a revoluble platen, of feed rolls, a frame in which said platen is adapted to be swung up clear 60 of said feed rolls to permit plies of web and carbon sheets to be straightened out beneath the platen, a support above the platen, a clip slidable upon said support and comprising jaws adapted to grip the plies of 65 web and carbon sheets, a handle for causing

said clip to seize or release the sheets and lying below the plane of the clip support, a line-spacing mechanism for said platen, a shaft on which said frame is adapted to be swung, a pinion forming part of said mechanism mounted on said shaft, and a connection for moving said clip by said pinion at the turning of the pinion. 70

12. In a typewriting machine, the combination with a traveling carriage and a revoluble platen, of feed rolls, a frame in which said platen is adapted to be swung up clear of said feed rolls to permit plies of web and carbon sheets to be straightened out beneath the platen, a support upon the platen, 75 a clip slidable upon said support and comprising jaws adapted to grip the plies of web and carbon sheets, a handle for said clip lying below the plane of the clip support, a line-spacing mechanism for said platen, 80 a shaft on which said frame is adapted to be swung, a pinion forming part of said mechanism mounted on said shaft, a reel slidable connected with said pinion, a cord adapted to be wound on said reel, and pulleys 85 adapted to cause the winding of the cord to move the clip line-space distances. 90

13. In a typewriting machine, the combination with a traveling carriage and a revoluble platen, of feed rolls, a frame in which 95 said platen is adapted to be swung up clear of said feed rolls to permit plies of web and carbon sheets to be straightened out beneath the platen, a clip above the platen to hold the web plies and an outside carbon sheet while a work-sheet is being inserted in front thereof, a rack upon which said clip is adapted to be set at line space intervals, a spring pawl for holding the clip positioned along the rack, and spring-operated jaws for the clip normally adapted to grip a web ply and adapted to be released. 100

14. In a typewriting machine, the combination with a traveling carriage and a revoluble platen, of feed rolls, a frame in 110 which said platen is adapted to be swung up clear of said feed rolls to permit plies of web and carbon sheets to be straightened out beneath the platen, a clip above the platen to hold the web plies and an outside carbon sheet while a work-sheet is being inserted in front thereof, a rack upon which said clip is adapted to be set at line-space intervals, a spring pawl for holding the clip positioned along the rack, spring-operated 115 jaws for the clip normally adapted to grip a web ply and adapted to be released, and a finger-piece for shifting the clip and adapted to release the pawl to permit said shifting. 120

15. In a typewriting machine, the combination with a traveling carriage and a revoluble platen, of feed rolls, a frame in which said platen is adapted to be swung up clear of said feed rolls to permit plies of web and carbon sheets to be straightened out 130

beneath the platen, a shaft on which said frame is journaled, a line-space mechanism including a pinion upon said shaft, a clip, for holding the leading edge of the web, and 5 a friction clutch connected to said pinion and adapted to advance said clip.

16. In a typewriting machine, the combination with a traveling carriage and a revoluble platen, of feed rolls, a frame in 10 which said platen is adapted to be swung up clear of said feed rolls to permit plies of web and carbon sheets to be straightened out beneath the platen, a clip above the platen to hold the web plies and an outside 15 carbon sheet while a work-sheet is being inserted in front thereof, a line-space mechanism for the platen, and means for automatically advancing the clip at corresponding line-space intervals.

20 17. In a typewriting machine, the combination with a revoluble platen, of feeding devices co-operating therewith, a swinging frame for said platen to lift the same clear 25 of said feeding devices, a clip above the platen to hold the leading edges of work-sheets and carbon-sheets operatively positioned on the latter, a guide upon which said clip is slidable, and means to hold said clip at line-space intervals on said guide.

30 18. In a typewriting machine, the combination with a revoluble platen, of feeding devices to co-operate therewith, a swinging frame to lift said platen clear of the feeding devices, a support above the platen, a 35 leading-edge clip slidable upon said support, a line-space mechanism for said platen, a pinion rotatable about the axis on which said frame swings, said pinion forming a part of the line-space mechanism, and means 40 whereby rotation of said pinion will cause said clip to be advanced.

19. In a typewriting machine, in combination, a platen around which work-sheets are fed, a clip to grasp the leading edges of 45 work-sheets positioned on said platen, a guide along which said clip is slidable, and line-space mechanism for shifting said clip.

20. In a typewriting machine, in combination, means including a revoluble platen for 50 feeding work-sheets, a clip to grasp the leading edges of work-sheets positioned on said platen, line-space mechanism for said platen, and a connection between said line-space mechanism and said clip, whereby actuation 55 of the former will effect line-space actuation of the latter.

21. In a typewriting machine, in combination, a platen, a clip to grasp the leading edges of work-sheets on said platen, means 60 effective at letter-space intervals to hold said clip against rearward movement, and line-space means effective at each operation to advance said clip from one holding position to another.

65 22. In a typewriting machine, in combina-

tion, line-space mechanism to advance work-sheets, a clip to engage the leading edges of said work-sheets, a manually-releasable device, effective at letter-space intervals to prevent backward movement of said clip, 70 and a connection between said line-space mechanism and said clip, whereby actuation of the former will advance the latter, said connection including a friction device normally effective in advancing the clip, but 75 adapted to permit a return movement of the clip when said manually-releasable device is released.

23. In a typewriting machine, in combination, a clip for engagement with the leading 80 edges of work-sheets, line-space mechanism, and a slip connection between said clip and said line-space mechanism, whereby the former will normally be advanced by the latter, but rearward movement of the clip will 85 be permitted.

24. In a typewriting machine, in combination, a platen, a clip to grasp at their leading edges a plurality of sheets, including a carbon-sheet and a sheet on which a 90 carbon-copy is to be made, a scale to indicate, by the position of the leading edge of a work-sheet on which typing is to be effected, the number of the printing line of the last-mentioned sheet, and line-space 95 mechanism adapted, at each actuation, to advance said clip and thereby advance the leading edges of the sheets clipped thereby from one division of said scale to another.

100 25. In a typewriting machine, in combination, a platen, a support to receive work-webs from the delivery side of the platen, a leading-edge clip comprising a base member slidable on said support in the direction of web-feed, a normally ineffective movable clip member pivoted at an intermediate point on said base member and having leading-edge aligning lugs extending downwardly on each side of the base 105 member, and means to render said movable clip member effective.

26. In a typewriting machine, in combination, a platen, a support to receive work-webs from the delivery side of the 115 platen, said support having on its rear face notches at line-space intervals, a leading-edge clip comprising a base member slidable on said support in the direction of web-feed, a normally ineffective movable clip member pivoted at an intermediate point on 120 said base member and having leading-edge aligning lugs extending downwardly on each side of the base member, means to render said movable clip member effective, and a pawl pivoted on said base member, so that it may engage the notches in the support, and having a finger projecting upwardly at a point clear of the leading edges 125 of work-webs gaged by the lugs, said finger 130

serving as a means to move said pawl to ineffective position and to shift the clip.

27. In a typewriting machine, in combination, a platen, a support to receive work-webs from the delivery side of the platen, a leading-edge clip comprising a base member slideable on said support in the direction of web-feed, a normally ineffective movable clip member pivoted at an intermediate point on said base member and having leading-edge aligning lugs extending downwardly on each side of the base member, and means to render said movable clip member effective comprising a cam having a dwell portion to maintain the movable clip member in effective position when shifted by the cam.

28. In a typewriting machine, in combination, a platen, a support to receive work-webs from the delivery side of the platen comprising a central member having notches at line-space intervals on its rear face, a leading-edge clip comprising a base member slideable on said central member, a normally ineffective movable clip member, lugs extending upwardly from said base member to furnish a pivotal support for said movable clip member, lugs extending downwardly from said base member on each side of said central member, a shaft extending through the downwardly-extending lugs, a handle fixed on said shaft, a cam fixed on said shaft, said cam being adapted to shift said movable clip member to effective position and having a dwell portion to lock said movable clip member in effective position, and a pawl loosely mounted on said shaft and normally urged to effective position to co-operate with said notches.

29. In a typewriting machine, in combination, a platen, a support to receive work-webs from the delivery side of the platen comprising a central plate having on its back face notches at letter-space intervals, a clip slideable on said plate comprising side members having rabbets at their upper and inner edges to receive the edges of said plate, means to hold the plate in the rabbets comprising a bar with an upper gripping surface extending across said plate and secured to said side members, single lugs extending upwardly from each of said side members, an upper clip member pivoted in said lugs, the operating arm of the upper clip member having a portion extending along the outer side of one of said side members, and a cam to engage and actuate said operating arm to render the upper clip member effective.

30. In a typewriting machine, the combination with a traveling carriage and a revolute platen, of feed rolls, a shaft mounted on said carriage, a platen-supporting frame mounted on said shaft so as to enable the

platen to be swung clear of the feed rolls to permit plies of web and carbon-sheets to be straightened beneath the platen, a support above the platen, a clip to hold the web plies and carbon-sheets, said clip lying close against the support and slideable thereon, a line-space mechanism for said platen including a pinion on said shaft, said pinion having a projecting hub, a rotatable member mounted on said hub, a friction device tending to cause said rotatable member to rotate with said pinion, and an operating connection between the rotatable member and the clip whereby the latter may be actuated by the former.

31. In a typewriting machine, the combination with a traveling carriage and a revolute platen, of feed rolls, a shaft mounted on said carriage, a platen-supporting frame mounted on said shaft so as to enable the platen to be swung clear of the feed rolls to permit plies of web and carbon-sheets to be straightened beneath the platen, a support above the platen, a clip to hold the web plies and carbon-sheets, said clip lying close against the support and slideable thereon, a line-space mechanism for said platen including a pinion on said shaft, said pinion having a projecting hub, a rotatable member mounted on said hub, a collar fixed on the end of the hub, a spring mounted between said collar and said rotatable member to urge the same toward the pinion to cause it to rotate therewith, and an operating connection between the rotatable member and the clip whereby the latter may be actuated by the former.

32. In a typewriting machine, the combination with a traveling carriage and a revolute platen, of feed rolls, a pivotally mounted platen-supporting frame whereby the platen may be swung clear of the feed rolls to permit plies of web and carbon-sheets to be straightened beneath the platen, a paper-table above the platen and comprising extensions, a turned-up edge on one extension forming a side gage for the plies of web, a turned-up edge on the other extension forming a side gage for a separate work-sheet, said last-mentioned extension having on its front face a line-spaced scale to be exposed between the turn-up edge and the adjacent edges of the plies of web and carbon-sheets, and on the rear face a line-space scale to facilitate positioning the leading edge of the separate work-sheet when the frame is turned with the front scale facing downward, and a clip to grip the leading edges of the plies of web and carbon-sheets to hold the same against the table.
